DISPENSER FOR TAPE

Mark B. Andrews, Kirkwood, Mo.

Application March 25, 1947, Serial No. 736,928

14 Claims. (Cl. 242—55.4)

1

The present invention relates to a dispenser for tape. More particularly, it relates to a dispenser for holding a plurality of rolls of tape, such as that used for indicating prices or the like, in such wise that any selected one of the rolls may be employed to supply tape for use at any time.

An object of the invention is to provide a tape dispenser that will conveniently hold a plurality of rolls of tape, and which has a support for these rolls that may be moved to dispose any selected roll in a dispensing position. A further object of the invention is to provide such a mechanism wherein the rolls may be easily replenished as required.

A further object of the invention is to provide a dispenser of this type that is particularly adapted for use with pressure-sensitive cellophane tape. A particular object of the invention is to provide a dispenser for use with cellophane tape in several rolls, with means for holding the end of each roll, and means for holding all of the rolls movably so that a selected one may be brought to position for dispensing therefrom. A particular object is to provide a dispenser as in the preceding sentence, wherein a cutter is located on the frame that supports the movable holder, and wherein each of the rolls is selectively brought adjacent this cutter for the removal of tape therefrom.

Other objects will appear from the description to follow.

In the drawings:

Fig. 1 is a front elevation of the dispenser;

Fig. 2 is an edge view thereof, taken from the bottom of Fig. 1;

Fig. 3 is a rear elevation partly broken away, taken from the back of Fig. 1;

Fig. 4 is a transverse section, taken substantially on the line 4—4 of Fig. 1; and

Fig. 5 is a section taken on the line 5—5 of Fig. 1.

The dispenser includes a support 10 that may be in the form of an elongated member having a hub 11, a handle 12, and opposite the handle a transversely extending ledge element 13. This ledge supports a severing blade 14.

The hub receives a swivel pin 16. A disc 18 has a hub 19 also engaged with the pin 16, so that the disc is rotatable on the support 10. Around the periphery of the disc 18 are several tape holding devices, generally indicated at 21. Each has a headed pin 22 permanently attached into the disc. Each pin receives a pair of blocks 23 that are rotatably mounted upon the pin and may be separated in suitable manner by separat-

2

ing washers 24. Likewise, they may be kept from surface engagement with the disc 18 by hub-like projections 25 adjacent the junction of the pins 22 with the disc.

These blocks 23 are preferably flat on opposite sides, as shown at 27. Each one is designed to receive and frictionally support the pasteboard ring core 28 of a roll of tape 29. The blocks are sized so that the tape rolls may be slipped over them and will be held for convenient removal, but will be held against accidental removal.

Outwardly from each of the pins 22, there is a pin 31 that may desirably be mounted in a projection 32 extending from the periphery of the disc 18. These pins 31 constitute means to hold the ends of the tape strips from the tape rolls on adjacent tape holding devices. The pins extend from the disc 18 outwardly so as to be disposed across, but in somewhat spaced relationship to the rolls of tape that are mounted upon each pin, or across a single wide roll if the mounting be so.

The use of the device is as follows:

One of the particularly valuable uses for this dispenser is in connection with price marking, in which case there may be ten tape roll holders, providing ten numerals from which all combinations of prices may be derived. Other numbers of rolls may be employed with the minor modifications that would be obvious.

When a particular number is desired, the operator, holding the handle 12 in one hand, turns the disc 18 until the number is located adjacent the transverse bar 13 and the blade 14. Thereupon, he draws the end of the tape forward until the proper amount to be severed is beyond the edge of the blade 14. He can then draw the tape tight by moving the thumb of his other hand, engaging the handle 12, against one of the projections 32. While thus holding the disc 18 with one hand, and the end of the tape with the other, the operator draws the free end of the tape across the edge of the blade 14, thereby severing the amount desired.

It will be seen that in this operation, as it is normally performed, the final free end of the tape will engage over the adjacent rod 31, and there stick so that the tape cannot fall off of the block 23, nor can the block spin around so that the tape end may roll back onto the main body of the tape and thereby present difficulty in restarting a removal. When the tape end is engaged onto a pin 31, it may be readily grasped, as a free portion normally projects beyond the pin 31, and, even if the tape terminates at the pin 31,

it can easily be pulled off such pin so as to be accessibly outstanding from the main body on the roll. This latter feature is a valuable one having more general application than to this dispenser, although particularly desirable herein.

What is claimed is:

1. In a portable dispenser for tape and the like, a support including a handle portion for supporting said dispenser during use, a severing device on the support, a rotatable member on the support, a plurality of tape holding means on the rotatable member, said tape holding means being disposed around the center of the rotatable member.

2. In a portable dispenser for tape and the like, a support including a handle portion for supporting said dispenser during use, a severing device on the support, a rotatable member on the support, a plurality of tape holding means on the rotatable member, said tape holding means being disposed around the center of the rotatable member, and fixed members attached to the rotatable member, there being one fixed member for each tape holding means, the fixed members extending adjacent the tape holding means for engagement with tape ends of tape rolls on said tape holding means.

3. In a portable dispenser for tape and the like, a support including a handle portion for supporting said dispenser during use, a severing device on the support, a rotatable member on the support, a plurality of tape holding means on the rotatable member, said tape holding means being disposed around the center of the rotatable member, and tape end receiving means rigidly mounted on the rotatable member, there being one such receiving means adjacent each tape holding means.

4. In a portable dispenser for tape and the like, a support including a handle portion for supporting said dispenser during use and having a bearing portion and a transversely projecting arm, a rotatable member, pivot means engaging the support at its bearing portion and engaging the rotatable member to attach the member to the support for rotation thereon, the transverse arm on the support extending adjacent the edge of the rotatable member and having a severing means thereon, and a plurality of tape spool holding means rotatably supported on the rotatable member, and arranged around the pivot means.

5. In a dispenser for tape and the like, a support having a bearing portion and a transversely projecting arm, a rotatable member, pivot means engaging the support at its bearing portion and engaging the rotatable member to attach the member to the support for rotation thereon, the transverse arm on the support extending adjacent the edge of the rotatable member and having a severing means thereon, a plurality of tape spool holding means rotatably supported on the rotatable member, and arranged around the pivot means, said tape spool holding means comprising pins attached at one end to the rotatable member, blocks pivotally mounted on the pins for frictional engagement with the cores of tape rolls, and fixed means on the rotatable member in position to be engageable by the tape on each holding means, for assuring retention of the tape rolls on the rotatable member.

6. In a tape dispenser, an elongated support comprising a handle portion, and a cutter portion, at opposite ends of the support, a member rotatably attached to the support between the handle portion and the severing portion, the rotatable member having a plurality of tape holding devices arranged around its periphery and

movable, by rotation of the rotatable member, to bring a selected tape holding device adjacent the cutter portion.

7. In a tape dispenser, an elongated support comprising a handle portion, and a cutter portion, at opposite ends of the support, a member rotatably attached to the support between the handle portion and the severing portion, the rotatable member having a plurality of tape holding devices arranged around its periphery and movable, by rotation of the rotatable member, to bring a selected tape holding device adjacent the cutter portion, and means on the rotatable member projecting therefrom and engageable by the hand at the handle, for holding the rotatable member still.

8. In a tape dispenser, an elongated support comprising a handle portion, and a cutter portion, at opposite ends of the support, a member rotatably attached to the support between the handle portion and the severing portion, the rotatable member having a plurality of tape holding devices arranged around its periphery and movable, by rotation of the rotatable member, to bring a selected tape holding device adjacent the cutter portion, means on the rotatable member projecting therefrom and engageable by the hand at the handle, for holding the rotatable member still, and tape retaining means adjacent each tape holding device.

9. A device of the type described, comprising an elongated support member; a longitudinally extending handle portion at one end of said support member; a disc-like member rotatably mounted on the support member; and a plurality of tape roll supporting means rotatably mounted on the disc-like member adjacent the periphery thereof.

10. A device of the type described, comprising an elongated support member; a longitudinally extending handle portion at one end of said support member; an arm-like portion extending normal to the support member at the other end thereof; tape severing means fixedly mounted on said arm-like portion; a disc-like member rotatably mounted on the support member; and a plurality of tape roll supporting means rotatably mounted on the disc-like member adjacent the periphery thereof.

11. A device of the type described, comprising an elongated support member, a longitudinally extending handle portion at one end of said support member; a disc-like member rotatably mounted on the support member; a plurality of tape roll supporting means rotatably mounted on the disc-like member about the center thereof; and a plurality of stud-like members fastened at one end to the disc-like member and extending normal thereto adjacent the periphery of said disc-like member.

12. A device of the type described, comprising a support member; a handle portion adjacent one end of said support member; a tape severing means adjacent the other end of said support member; a member rotatably mounted on the support member; a plurality of tape roll supporting means mounted on the rotatable member about its center of rotation; a series of fixed elongated members fastened to the rotatable member beyond the tape roll supporting means, an elongated member being between the tape severing means and a tape roll supporting means when the tape from a roll is in position to be severed whereby the severed end of the tape re-

maining on the roll will fall across the elongated member.

13. In a tape dispenser, an open frame support member including a handle portion for supporting the dispenser during use; a flat member rotatably mounted on the support member; a series of pin-like members fixedly fastened to the rotatable member about its center of rotation; and at least one tape roll supporting member rotatably mounted on each pin-like member and having one end thereof unobstructed to receive a roll of tape.

14. In a tape dispenser, a support member; a flat member rotatably mounted on the support member; a series of pin-like members extending normal to the rotatable member about its center of rotation; and at least one tape roll supporting member rotatably mounted on each pin-like member; said tape roll supporting member being

substantially cylindrical in shape and having opposed flat surfaces formed parallel to the axis of rotation.
